(57) **ABSTRACT**

A method of digital printing and finishing for fabrics is provided. The method includes a step of unwinding a fabric from a first reel. A step of compensating the speeds and of spreading the fabric for its positioning on a conveyor belt provided with supporting elements on which a digital printing step occurs is provided. A step of drying the fabric is provided. A step of winding the fabric onto a second reel is provided. These steps are being executed at corresponding stations arranged in sequence with respect to each other and the fabric passing through them continuously, transversely to the conveyor belt, there being a plurality of bars provided with printing heads which are controlled electronically and synchronized with the movement of the conveyor belt.

DIGITAL PRINTING AND FINISHING
METHOD FOR FABRICS AND THE LIKECROSS-REFERENCE TO RELATED
APPLICATIONS

This application is a continuation of U.S. patent application Ser. No. 17/090,514 filed on Nov. 5, 2020, now U.S. Pat. No. 12,043,046, which is a continuation of U.S. patent application Ser. No. 15/214,037 filed on Jul. 19, 2016, now abandoned, which is a continuation of U.S. patent application Ser. No. 13/988,108 filed on May 17, 2013, now abandoned, which is a U.S. national phase of PCT Application No. PCT/EP2011/067162 filed on Sep. 30, 2011, which claims priority to Italian Application No. MI2010A002176, filed Nov. 24, 2010, the disclosures of which are incorporated in their entirety by reference herein.

TECHNICAL FIELD

The present invention relates to a digital printing and finishing method for fabrics and the like.

BACKGROUND ART

The conventional method of digital printing and finishing for fabrics, starting with a fabric for conventional printing that has previously been rendered hydrophilic in order to allow the penetration of conventional printing pastes, is made up of a sequence of steps that are executed independently of each other.

More precisely, this sequence consists in a step of preparing the fabric for digital printing, in which the fabric for conventional printing is impregnated with adapted substances in order to enable the fixing of the color in order to subsequently be dried, a printing step, in which the fabric is printed and dried, a steaming step, in which the fabric is placed in a steaming chamber for a period that can vary from ten to thirty minutes according to the type of fabric and to the type of printing ink used, a washing step, in which the fabric is washed to remove excess quantities of ink, and a drying step, in which the fabric is dried.

This conventional method suffers the drawback of displaying limited productivity because of the fact that the individual steps occur independently of each other.

In order to speed up the method of printing, a known technique is to have the washing and drying steps occur continuously. This attempt at speeding the method up is however not sufficient to adequately reduce the processing times.

DISCLOSURE OF THE INVENTION

The aim of the present invention consists in providing a method of digital printing and finishing for fabrics that is faster than the conventional method of digital printing and finishing, while increasing the productivity of the system.

Within this aim, an object of the present invention consists in providing a method of digital printing and finishing for fabrics that is simple and effective, while at the same time ensuring low costs of implementing the system and production costs that are economically advantageous when compared to those of the known art.

Another object of the present invention is to provide a method of digital printing and finishing for fabrics that limits manual intervention from the operator as far as possible.

2

Another object of the present invention is to provide a method of digital printing and finishing for fabrics that, thanks to its peculiar implementation characteristics, is capable of offering the widest guarantees of reliability and safety in use.

This aim and these and other objects which will become better apparent hereinafter, are achieved by a method for printing and finishing for fabrics and the like, characterized in that it comprises a step of unwinding a fabric from a first reel, a step of compensating the speeds and of spreading said fabric in order to position it on a conveyor belt provided with supporting means on which a digital printing step occurs, followed by a step of drying said fabric and a step of winding said fabric onto a second reel, said steps being performed in corresponding stations arranged in sequence with respect to each other and said fabric passing through said stations continuously, transversely to said conveyor belt there being a plurality of bars provided with printing heads which are controlled electronically and synchronized with the movement of said conveyor belt.

BRIEF DESCRIPTION OF THE DRAWINGS

Further characteristics and advantages of the invention will become better apparent from the detailed description of two preferred, but not exclusive, embodiments of a method of printing and finishing for fabrics and the like, which are illustrated by way of non-limiting example in the accompanying drawings, wherein:

FIG. 1 is a schematic side elevation view of a system according to a first embodiment of a method of printing and finishing for fabrics and the like, according to the present invention;

FIG. 2 is an enlarged-scale detailed view of the station corresponding to the printing step of the system shown in FIG. 1;

FIG. 3 is a schematic plan view from above of the station shown in FIG. 2;

FIG. 4 is a schematic side elevation view of a system according to a second embodiment of a method of printing and finishing for fabrics and the like, according to the present invention.

WAYS OF CARRYING OUT THE INVENTION

With reference to the figures, the first embodiment of the method of printing and finishing for fabrics and the like, according to the invention, is performed by a system, generally designated in FIG. 1 by the reference numeral 1a, and comprises a step of unwinding a fabric 2 from a first reel 3, a step of compensating the speeds and of spreading the fabric 2 in an adapted station 4 for positioning it on a conveyor belt 5 provided with supporting means, for example of the adhesive type, on which a digital printing step occurs.

Advantageously, transversely to the conveyor belt 5, there is a plurality of bars 6 provided with printing heads 7 which are controlled electronically and synchronized with the movement of the conveyor belt 5.

More precisely, the printing heads 7 are of the piezoelectric ink-jet type and are positioned on each one of the bars 6 in such a manner as to cover the width of the conveyor belt 5 and allow continuous printing.

Subsequently a step of drying the fabric 2 and a step of winding it onto a second reel 11 are provided. This drying step can occur with hot air in a steaming chamber 12 or the like.

Differently, in the second embodiment, for which the corresponding system **1b** is shown in FIG. 4, between the unwinding station and the printing station a step can be provided of immersion of the fabric **2** unwound from the first reel **3** in a tank **8** containing an aqueous solution **9** comprising at least one or more substances selected from the group constituted by pH stabilization compounds and salts adapted to facilitate the fixing of the ink on the fabric **2** in the subsequent steaming step described below.

Conveniently, following the above mentioned immersion, a step is provided of pressing the fabric **2** impregnated with the aqueous solution **9** through a pair of presser rollers **10** in such a manner as to eliminate the excess part of the aqueous solution **9** from the fibers of the fabric **2**.

Following the digital printing step, a step is provided of steaming the fabric **2** printed and impregnated with the aqueous solution **9** through a steaming chamber **12** in such a manner as to fix the ink to the fabric **2**.

In this step, the fabric **2** retains a level of humidity similar to that of the previous steps and, given the speed at which this step occurs, which is comprised between 1 and 100 meters per minute, is such as to accelerate the process of penetration of the color into the fibers of the fabric **2**.

Moreover, thanks to a steam temperature that is adapted to the process under conditions of atmospheric pressure, it is sufficient for the fabric **2** to remain in the steaming chamber **12** for 10 to 40 seconds in order to obtain the required fixing.

Conveniently, the steaming chamber **12** is dimensioned as a function of the top speed of the printing step, so as to ensure that the fabric **2** remains inside the steaming chamber **12** for a sufficient time.

Thereafter, a step can be provided of washing the printed and steamed fabric **2** which is adapted to eliminate from the fabric **2** the excess part of the ink by means of immersion in an adapted tank **13**.

The fabric **2** is then dried and brought back to its initial size through two adapted machines **14** and **15** or it is simply dried and subsequently rewound onto the reel **11**.

To sum up, in both of the proposed embodiments, the method according to the invention comprises a sequence of steps performed in corresponding stations arranged in sequence with respect to each other with the fabric **2** passing through all of them continuously.

More precisely, with regard to the first embodiment, the continuous method of digital printing and finishing, according to the invention, is adapted, for example, to fabrics printed with acid or disperse inks and, with regard to the second embodiment, the continuous method of digital printing and finishing, according to the invention, is adapted, for example, to fabrics printed with reactive inks such as monochloro/dichloro triazine and vinyl sulfone.

In practice it has been found that the method of digital printing and finishing for fabrics and the like, according to the present invention, achieves the intended aim and objects in that it is much faster than the conventional methods of digital printing.

Another advantage of the method, according to the present invention, consists in that it enables an energy saving as a result of the reduction of the number of drying processes and the reduction of the evaporation time.

A further advantage of the method, according to the present invention, consists in that, thanks to the continuity of the process, the movement is eliminated of the fabric between the several necessary steps to obtain the required product.

The method of printing and finishing for fabrics and the like thus conceived is susceptible of numerous modifications and variations, all of which are within the scope of the appended claims.

For example, instead of having the fabric on reels both in input and in output, it can be arranged in sheets.

Moreover, all the details may be substituted by other, technically equivalent elements.

In practice the materials employed, provided they are compatible with the specific use, and the contingent dimensions and shapes, may be any according to requirements.

The disclosures in Italian Patent Application No. MI2010A002176 from which this application claims priority are incorporated herein by reference.

15

The invention claimed is:

1. A method of digitally printing a fabric, the method comprising:

supplying a fabric to a continuously moving conveyor belt, while compensating a speed of the conveyor belt with a speed of the supplied fabric;

adhering the supplied fabric to the conveyor belt; with the fabric adhered to the conveyor belt, digitally printing an ink onto the fabric using fixed ink-jet printing heads, while continuously moving the conveyor belt and electronically controlling the printing heads and synchronizing the printing heads with movement of the conveyor belt, thereby allowing continuous printing of the fabric; and then

removing the printed fabric from the continuously moving conveyor belt.

2. The method of claim 1, further comprising, before adhering the supplied fabric to the conveyor belt, applying an ink-fixing solution to the supplied fabric.

3. The method of claim 2, wherein applying the ink-fixing solution comprises impregnating fibers of fabric with the ink-fixing solution before the fabric reaches the conveyor belt.

4. The method of claim 3, wherein the step of digitally printing comprises digitally printing the impregnated fibers.

5. The method of claim 3, wherein applying the ink-fixing solution comprises immersing the fabric in a tank containing the ink-fixing solution.

6. The method of claim 2, further comprising eliminating excess ink-fixing solution from the fabric before digitally printing the fabric.

7. The method of claim 2, wherein the ink-fixing solution is an aqueous ink-fixing solution.

8. The method of claim 7, wherein the aqueous ink-fixing solution comprises pH stabilization compounds, pH stabilization salts or mixtures thereof.

9. The method of claim 1, wherein supplying the fabric comprises unwinding the fabric from a reel.

10. The method of claim 1, further comprising, after digitally printing the ink, drying the fabric.

11. The method of claim 10, further comprising fixing the ink on the printed fabric between the digital printing and the drying.

12. The method of claim 11, wherein fixing the ink comprises steaming the printed fabric in a steaming chamber.

13. The method of claim 12, further comprising, between the steaming and the drying, washing the printed and steamed fabric to eliminate excess ink.

14. The method of claim 12, wherein steaming the printed fabric comprises maintaining the fabric at atmospheric pressure in the steaming chamber for 10 to 40 seconds.

60

65

15. The method of claim 1, after removing the printed fabric from the conveyor belt, winding the printed fabric onto a reel or arranging the printed fabric in sheets.

16. The method of claim 1, wherein adhering the fabric to the conveyor belt comprises adhesively adhering the fabric to the conveyor belt. 5

17. The method of claim 1, wherein the printing heads are arranged so as to cover an overall width of the conveyor belt.

18. The method of claim 1, wherein digitally printing the fabric comprises applying reactive inks. 10

19. The method of claim 1, wherein the printing heads are mounted to a plurality of bars transversally extending above the conveyor belt.
